ATTORNEYS

UNITED STATES PATENT OFFICE.

ADAM RANDOLPH BROWN, OF LOUISVILLE, KENTUCKY.

TOY MACHINE GUN.

Application filed April 22, 1922. Serial No. 556,041.

To all whom it may concern:

Be it known that I, ADAM R. BROWN, a citizen of the United States, and a resident of Louisville, in the county of Jefferson and 5 State of Kentucky, have invented new and useful Improvements in Toy Machine Guns, of which the following is a full, clear, and exact description.

This invention relates to improvements in 10 toys, particularly toy machine guns, an object of the invention being to provide a toy of this character which will prove interesting and amusing to children, and a device which will be efficient in operation, and easy to 15 manipulate.

Still another object is to provide a toy machine gun which will be simple and practical in construction, strong and durable in use, and which can be manufactured with 20 comparative economy.

With these and other objects in view, the invention consists in certain novel features of construction, and combinations and arrangements of parts as will be more fully 25 hereinafter described and pointed out in the claims.

In the accompanying drawings:—

Figure 1 is a perspective view of my improved toy; 30 Figure 2 is a view in longitudinal section therethrough; and

Figure 3 is a fragmentary view in rear elevation thereof.

Referring in detail to the drawings, I 35 have used the reference numerals 1, 1 to designate a pair of plates spaced apart and each secured at its forward edge to the upper end of a leg or standard 2. Cooperating with the leg 2 to form a supporting frame 40 for the plates are a pair of inclined legs 3 secured to the outside faces of the plates adjacent their lower rear corners. A strengthening cross bar 4 connects the legs 3. A brace 5 between the leg 2 and the cross bar 4 tends 45 to lend rigidly to the construction.

An opening 6 in the leg 2 adjacent its upper end accommodates the inner or breech end of a barrel 7. The barrel is slightly inclined and immediately thereabove and 50 resting thereon, I provide a bullet chamber 8 of tubular shape which is likewise inclined, and at its lower end near the breech of the barrel is provided with an opening 9, registering with an opening 10 in the top 55 of the barrel to permit the gravitational delivery of the bullets 11 into the barrel.

These bullets are preferably in the form of rubber balls. The closed rear end of the chamber may also be accommodated in the opening 6 and held in place by a screw 12 60 or other suitable securing device.

I have used the reference numeral 13 to designate an ejector in the form of a rod having one end located in the breech of the barrel just behind the opening 10 and its 65 other enlarged end 14 riding in grooves 15 on the inner faces of the plates. A block 16 is secured to the rear face of the leg 2 just below the plates and a flat spring 17 having one end fixed to the block engages at 70 its free end with the ejector 13 tending to normally hold the same in the retracted position shown in Figure 2.

I provide a novel form of mechanism for 75 striking the ejector to effect shooting of the bullets from the barrel. The striker itself is in the form of a relatively large flat spring 18 having one end secured to a block 19 fixed to the rear face of the leg 2 adjacent its lower end and tending to normally project the ejector into the barrel against the action of the weaker spring 17. The striker is forced rearwardly and then let fly against the ejector to shoot the bullets from the barrel by a trigger 20 mounted upon a crank 80 shaft 21 journalled in two upward extensions 22 of the plates 1. This trigger includes a pair of oppositely disposed arms 23 successively engageable with the free end of the striker 18 to move the same rearwardly and 85 then let the striker spring back against the ejector. A crank handle 23' may be provided for operating the crank arm to rotate the trigger and a handle 24 secured to the opposite plate 1 from the plate with which the crank handle is associated provides manually graspable means for firmly holding the frame of the gun in place as the handle is rotated.

A flexible device 25 secured to the frame 90 in any approved manner carries a cap 26 adapted to normally close the open outer end of the chamber 8 after the ammunition has been introduced therein.

The operation of the device is as follows: 105 The bullets or balls are first introduced into the chamber 8 and roll by gravity toward the inner end of the same. The size of the openings 9 and 10 in the chamber and barrel are such that the dropping of one ball 110 through these openings into the barrel, where it rests against the ejector 13, will ef-

fectively block the passage of other balls into the barrel. Rotation of the crank handle 23' (the operator meanwhile grasping the handle 24 with his other hand) will 5 cause the arms of the trigger to successively force the striker rearwardly and as one arm of the trigger slips over the top of the striker, the striker will fly back toward the position indicated in dotted lines in Figure 10 2, striking the ejector and propelling the bullet from the barrel. The movement of the ejector is limited by the movement of its enlarged end 14 in the groove 15. As the 15 other arm of the trigger upon continued rotation of the shaft 21 engages with the striker and again moves the striker rearwardly, the spring 17 will restore the ejector to its normal position and permit the dropping of another bullet into the breech of the 20 barrel. It will be seen from the foregoing description that the toy will be capable of rapid operation.

I have illustrated the preferred embodiment of the invention, but numerous slight 25 changes and alterations might be made in the general form and arrangement of the parts described without departing from the invention, and hence I do not wish to limit myself to the precise details set forth, but 30 shall consider myself at liberty to make such slight changes and alterations as fairly fall within the spirit and scope of the appended claims.

I claim:

35 1. In a toy machine gun, a plurality of plates held in spaced relation with respect to each other, a barrel carried by the plates and positioned therebetween, an ejector movable in the barrel and extending therefrom, 40 said plates being provided with cooperating grooves to receive that portion of the ejector extending beyond the barrel to maintain the same in alignment with the barrel.

2. In a toy machine gun, a pair of vertically disposed plates secured in spaced relation to one another, a barrel mounted between the plates and extending therebeyond, an ejector slidable in said barrel and extending therefrom between said plates, said 50 ejector being provided with an enlarged head and said plates being grooved adjacent to the breech end of the barrel to receive

said head to support the ejector in alignment with the barrel.

3. In a toy machine gun, a pair of plates 55 held in spaced relation, a support therefor, a gun barrel mounted between the plates, an ejector slidable in the barrel and extending therefrom between the plates, said extended portion having guided movement in the 60 plates and provided with a recess, a leaf spring carried by the support and engaging said recess to retain the ejector partly withdrawn from the barrel in a retracted position, a second leaf spring secured to the support and adapted to engage the ejector, and a revoluble armed trigger for moving the last named spring rearwardly and then releasing it.

4. In a toy machine gun, a pair of vertically disposed plates held in spaced relation, supports therefor, a gun barrel mounted between the plates, a magazine communicating with the barrel, an ejector 70 slidable in the barrel and extending therefrom between the plates, said extended end terminating in an enlarged head, said plates being provided with cooperating grooves to receive the head to maintain the said ejector in alignment with the barrel.

5. In a toy machine gun, a gun barrel, a magazine associated therewith, an ejector movable in the barrel, a striker mechanism engageable with the ejector to shoot a projectile from the barrel and a spring engaging the ejector to retract the same after firing to effect the loading of another projectile from the magazine.

6. In a toy machine gun, a support, a gun barrel secured at one end to the support, an 90 ejector movable therein and extending therefrom and having guided movement in the support, a magazine associated with the barrel, a spring engageable with the extended portion of the ejector to move the same to 95 a normally retracted position to load the barrel from the magazine, a leaf spring striker adapted to engage the end of the ejector and functioning to overcome the tension of said retractile spring to shoot a projectile from the barrel, and a revoluble trigger having arms for moving the striker rearwardly and then releasing it.

ADAM RANDOLPH BROWN.
